COIL ASSEMBLING MACHINE

John W. Kozak, Kenosha, Wis., assignor to Frank L. Wells Company, Kenosha, Wis., a corporation of Wisconsin

Application August 19, 1955, Serial No. 529,384

3 Claims. (Cl. 140—92.7)

This invention relates to new and improved apparatus for the forming and assembly of offset or crimped coil springs for use as cushioning elements in the mattress and furniture industries.

A widely used type of such coil spring assemblies comprises a plurality of adjacently placed, vertically extending coil springs with the springs linked together by means of helical lengths of wire which are screwed around adjacent touching portions of the top and bottom turns of the coil springs. The coil springs in general use have their top and bottom turns flattened with the ends of the coils wrapped around the top turns to form substantially complete circles. Another form of construction provides top and bottom turns with flattened and offset sections parallel with tangents to the circles formed by these turns. This construction affords adjacent flat areas on the closely spaced coils so that the coil connecting helical wires may be screwed around these flattened portions rather than curved touching portions of circular arcs. Such flattened areas thus provide more efficient and longer connected areas with greater flexibility and less binding in the assembled spring structure. These coils with flattened sections are, however, more expensive than the coils having generally circular end portions. Also, when inserted in the assembly machines these coils require exact orientation to bring the flattened portions of adjacent coils into parallel relation.

It is an object of the present invention to provide new and improved apparatus for the forming and assembly of offset or crimped coil springs.

It is a further object of the invention to provide a single machine which in successive steps forms adjacent contacting portions of coil springs and then connects the contacting portions.

It is an additional object to provide apparatus of this character which simultaneously forms the mating portions of two adjacent coil springs.

It is also an object to provide apparatus which is simple in design, construction and operation and adapted for use in combination with other features of standard commercial coil assembling machines.

Other and further objects will appear as the description proceeds.

I have shown a preferred embodiment of my invention in the accompanying drawings in which—

Figure 1 is a plan view of the apparatus with coils in place;

Figure 2 is a vertical section through the apparatus with coils in the forming dies;

Figure 3 is a view as seen from line 3—3 of Figure 2; and

Figure 4 is a fragmentary view, on an enlarged scale, showing the coils in the assembly position.

In the drawing, the base plate 11 is secured to a table supporting the coil assembling machine which has not been shown. The particular construction of the means for feeding the coils to the apparatus also forms no part of the present invention and has not been shown. The

2

fixed die holding member 13 is fitted on top of the plate 11 with lateral shoulders fitted under the overhanging flanges 15 of the guideway members 17, best shown in Figure 3. A fixed abutment member 19 is recessed in the base member 11, as shown in Figure 2. The movable die carrying member 21 is provided with shoulders 22 in the guideway 17 and is movable toward and away from the fixed die carrier member 13.

The bearing bracket 25 is secured to the underface of member 11 by the screws 27 and is one of a series of such brackets. These brackets 25 carry a shaft 29 on which is fixedly secured the bell crank 31. The portion of the bell crank 31 fitting around shaft 29 is bifurcated, as shown in Figure 3, and the drive arm 33 has its lower end fixedly secured on shaft 29 between the bifurcations. The upper end 35 of drive arm 33 fits in a recess 37 formed in the underface of the movable die carrying member 21. The bell crank member 31 has an upwardly extending arm 39 through which is threaded a drive screw 41. The inner end of this drive screw 41 engages the face of the drive arm 33 and the screw 41 is held in adjusted position by means of the lock nut 43. The lower end of bell crank member 31 has a laterally extending shaft 44 which carries a roller 45 which engages a cam 46 secured to shaft 47 by key 48, the shaft 47 being carried in the bracket 25.

As best shown in Figure 3, the roller 45 extends laterally of the bell crank 31 and into the closed raceway 49, shown in Figure 2, formed in the adjacent lateral face of the cam 46.

The opposed faces of the fixed and movable die carrying members 13 and 21, respectively, are provided with mating semi-cylindrical recesses 51 and 53, as best shown in Figure 2. Below these recesses the fixed member 13 carries an upper die 55 and a lower die 57. Similarly, the movable member 21 carries an upper die 59 and a lower die 61. These mating dies are designed to shape the terminal convolutions of the springs 65, shown in Figure 1, to give them the flattened offset mating portions 67 and the curved connecting portions 67a. It will be understood that before treatment in the die, the top and bottom portions of the coil springs are substantially circular, as shown at the left of spring 68 in Figure 1.

The vertically movable stripper plunger 69 is slidable in openings in the base plate 11, in similar openings formed in the fixed and movable die carrying members 13 and 21 and in aligned openings in the dies 55, 57, 59 and 61. The lower end of plunger 69 carries a roller 70 which rests upon the cam 71 carried by shaft 47 adjacent cam 46, the cam being keyed to the shaft and rotatable therewith.

In the operation of the apparatus, the shaft 47 is rotated so that the roller 45 is in the radially inward portion 78 of the cam race 49. This permits the lower arm 31 of the bell crank to swing to the left, as shown in Figure 2, which swings the movable die carrying member 21 to the right; thus separating it from the fixed die member 13. A previously crimped and formed spring, for example as shown at the right at 65, is lifted out of the space between the dies by the stripper plunger 69 which is lifted by a rise on cam 71 and is then moved laterally to the position in which it is shown in Figure 1. This lateral movement may be accomplished manually or by any desired mechanical means. The second spring 68, at the left of Figure 1, then has its terminal convolution inserted between the fixed die 13 and the movable die 21 so as to rest upon the adjacent circular and unformed terminal convolution of the right hand spring 65.

Rotation of shaft 47 lowers the stripper plunger 69 and the spring 65 moves down between the dies 57 and 61 while the superposed spring 68, resting on spring 65, has its arcuate edge moved down between the dies 55 and

59. The cam wheel 46 continues to rotate in the counter-clockwise direction and the radially outer portion 73 of the cam race 49 thrusts roller 45 and the lower portion of bell crank 31 to the right. This causes the head 35 of drive arm 33 to thrust the movable die carrying member 21 to the left until the parts reach the position shown in Figure 2. The mating dies 57 and 61 form the portion of spring 65 which is clamped between them as shown in Figure 1. Similarly, the mating dies 55 and 59 form the adjacent portion of spring 68 to the contour shown in Figure 1.

As the shaft 47 continues to rotate in the counter-clockwise direction, the roller 45 rises into the dwell 75 in cam race 46 which causes the bell crank 31 to move in the clockwise manner about shaft 29, thus moving the movable dies away from the fixed dies a sufficient distance so that the adjacent formed portions of springs 65 and 68 may be lifted by the stripper plunger 69 whose roller 70 is now engaged by a high portion 72 of cam 71. As the roller 45 moves out of the dwell 75 into the second high portion 77 of cam race 46, the fixed and movable die members are forced again to the position shown in Figure 2. At this time, however, being held up by the stripper plunger 69, the formed spring portions 67 of springs 65 and 68 are in the cylindrical passage formed between the members 13 and 21 by the recesses 51 and 53, as shown in Figure 4. While they are held in this position the spiral 81 is woven through the cylindrical passage about the matching formed portions 67 of springs 65 and 68; thus joining the springs. The weaving of the spiral may be done manually or mechanically by any well-known means.

After the weaving is completed the roller 45 moves down into a radially inward portion 78 of cam race 46; thus moving the movable die carrying member 21 and opening the cylindrical passage and the joined coils are lifted out of the cylindrical recess together with the spiral which has been woven through them to connect them. This lifting action is caused by a rise on cam 70 lifting the stripper plunger 69. The whole assembly is moved to the right to bring the left side of coil 68 over and into the space between the fixed and movable die carrying members and the process proceeds as before.

It will be understood that while a single unit has been shown, there will normally be a multiplicity of duplicate units located along the shafts 29 and 47 so that a plurality of coils are simultaneously formed and then woven together by a continuous spiral 81 extending the full length of the coil assembly.

The apparatus, therefore, is capable, when provided in any desired number, of simultaneously crimping and forming flat overlapping portions on a plurality of springs. It also holds the crimped springs in fixed position so that a plurality of pairs of springs may be secured together by a single continuous weaving operation. Thus the less costly springs with the circular upper and lower portions may be simply formed with matching flat segments and in the same apparatus held for weaving in the usual manner.

My improved apparatus is adapted for use with usual commercial types of coil assembling and weaving apparatus. Thus it may be used with any standard types of feeding and weaving apparatus.

While I have shown one preferred form of my apparatus, this is to be understood to be illustrative only as it is capable of modification to meet differing conditions and requirements and I therefore contemplate such varia-

tions as come within the spirit and scope of the appended claims.

I claim:

1. Apparatus for the forming and assembly of offset coil springs which comprises fixed die holding means and movable die holding means, a pair of dies carried one above the other by the fixed die holding means, a pair of dies carried by the movable die holding means in mating relation to the dies carried by the fixed die holding means, the upper and lower mating pairs of dies being formed to each offset a coil spring, the fixed and movable die holding means being provided with mating recesses to receive the offset coil portions and to hold them for weaving a spiral about the offset coil portions to hold them in assembled relation, means for lifting the offset coils from the dies to the mating recesses, and means for moving the movable die holding means toward and away from the fixed die holding means.

2. Apparatus for the forming and assembly of offset coil springs which comprises fixed die holding means and movable die holding means, a pair of dies carried one above the other by the fixed die holding means, a pair of dies carried by the movable die holding means in mating relation to the dies carried by the fixed die holding means, the upper and lower mating pairs of dies being formed to each offset a coil spring, the fixed and movable die holding means being provided with mating recesses to receive the offset coil portions and to hold them for weaving a spiral about the offset coil portions to hold them in assembled relation, the dies and fixed and movable die holding means being provided with mating vertically extending openings forming a vertical passage, a vertically movable stripper plunger operating in said passage, means for moving the plunger to lift the offset coil portions from the dies into the mating recesses in the fixed and movable die holding members, and means for moving the movable die holding means toward and away from the fixed die holding means.

3. Apparatus for the forming and assembly of offset coil springs which comprises fixed die holding means and movable die holding means, a pair of dies carried one above the other by the fixed die holding means, a pair of dies carried by the movable die holding means in mating relation to the dies carried by the fixed die holding means, the upper and lower mating pairs of die being formed to each offset a coil spring, the fixed and movable die holding means being provided with mating recesses to receive the offset coil portions and to hold them for weaving a spiral about the offset coil portions to hold them in assembled relation, the dies and the fixed and movable die holding means being provided with mating vertically extending openings forming a vertical passage, a vertically movable stripper plunger operating in said passage, means for moving the plunger to lift the offset coil portions from the dies into the mating recesses in the fixed and movable die holding members, and means for moving the movable die holding means toward and away from the fixed die holding means, the means for moving the plunger and the movable die member comprising a rotatable shaft located below the fixed and movable die members and cams rotated by said shaft.
